UNITED STATES PATENT OFFICE.

ELMER J. STROUT, OF UTICA, ILLINOIS.

PLUG HOLDER.

Application filed October 9, 1922. Serial No. 593,314.

To all whom it may concern:

Be it known that I, ELMER J. STROUT, a citizen of the United States, residing at Utica, in the county of La Salle and State 5 of Illinois, have invented new and useful Improvements in Plug Holders, of which the following is a specification.

This invention relates to a spark plug holder, the general object of the invention 10 being to provide a device for holding a spark plug so that it can be taken apart by a tool, using both hands on the tool or one hand free.

Another object of the invention is to provide means whereby the holder can be fastened to a part of the engine or any other support.

The invention also consists in certain other features of construction and in the 20 combination and arrangement of the several parts, to be hereinafter fully described, illustrated in the accompanying drawings and specifically pointed out in the appended claim.

25 In describing my invention in detail, reference will be had to the accompanying drawings wherein like characters denote like or corresponding parts throughout the several views, and in which:—

30 Figure 1 is a view showing the device in use and attached to the cylinder head of a motor.

Figure 2 is a similar view showing the device fastened by a horizontal bolt to a 35 support.

Figure 3 is an enlarged plan view of the device itself.

Figure 4 is a bottom view.

Figure 5 is a longitudinal sectional view.

40 Figure 6 is a view of one end of the device.

Figure 7 is a view of the opposite end thereof.

45 In these views 1 indicates a plate which has a socket 2 therein of the shape of the spark plug which it is designed to be used for. A circular hole 2' is formed in the under part of the plate and this hole regis-

ters with the socket so that the threaded part of the plug will extend through the hole with the wrench receiving part thereof in the socket. The plate is provided with a reduced part 3 which has a bolt receiving opening 4 therein so that it can be bolted to a cylinder head, as shown in Figure 1 or to any other support. The under side of the plate is provided with depending parts 5 which engage the support and help to hold the plate against movement. These depending parts are spaced apart to form a slot 6 so that the device can be placed over a bolt 7 or the like in order to hold the device in position when it cannot be fastened by a bolt passing through the hole 4. Each part 5 is provided with a bracing part 5' which connects it with the bottom of the plate.

From the above it will be seen that the device provides a handy tool for disassembling spark plugs and it will leave both hands free to manipulate the wrench and handle the parts of the plug. It also takes the place of a vise.

It is thought from the foregoing description that the advantages and novel features of my invention will be readily apparent.

I desire it to be understood that I may make changes in the construction and in the combination and arrangement of the several parts, provided that such changes fall within the scope of the appended claim.

Having thus described my invention what I claim is:—

A spark plug holder comprising a plate having a socket in its upper part shaped to fit a spark plug and a hole in the lower part which passes through the bottom wall of the socket, a rear extension on the plate of less thickness than the plate and having a hole therein and a depending part on the plate having its rear face extending at right angles to the bottom of the extension, said depending part having a slot therein and bracing parts connecting the depending part with the bottom of the plate.

In testimony whereof I affix my signature.

ELMER J. STROUT.
